Des. 78,614

UNITED STATES PATENT OFFICE.

ALBERT C. BROWN, OF CHICAGO, ILLINOIS.

DESIGN FOR A FAUCET HANDLE.

Application filed August 4, 1928. Serial No. 27,706. Term of patent 14 years.

To all whom it may concern:

Be it known that I, ALBERT C. BROWN, a citizen of the United States, residing at Chicago, county of Cook, and State of Illinois, have invented a new, original, and ornamental Design for Faucet Handle, of which the following is a specification, reference being had to the accompanying drawings, forming a part thereof.

On the drawings:

Fig. 2 is a side view thereof, and
Fig. 3 is a perspective view.

I claim:

The ornamental design for a faucet handle as shown.

ALBERT C. BROWN.
